UNITED STATES PATENT OFFICE.

FRANK C. BATES, OF KANSAS CITY, MISSOURI.

LIQUID-VENDING MACHINE.

Application filed November 25, 1921. Serial No. 517,448.

To all whom it may concern:

Be it known that I, FRANK C. BATES, a citizen of the United States, residing at Kansas City, in the county of Jackson and State of Missouri, have invented certain new and useful Improvements in Liquid-Vending Machines; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to liquid dispensing mechanism and it is particularly adapted for dispensing gasoline and the like, the primary object being to provide means whereby the dispensing apparatus will be come effective upon the introduction of a check, coin or token of appropriate denomination into the machine.

The mechanism is such that it operates as a coin-controlled mechanism although the coin control chute and its complementary parts so far as the present invention is concerned is not an important feature.

The specific construction of the device selected for illustration will be apparent by reference to the following description in connection with the accompanying drawings, in which

Fig. 1 is a perspective view of a dispensing apparatus constructed in accordance with my invention, parts being broken away to show the interior construction thereof.

Fig. 2 is a vertical, longitudinal, sectional view through the base casing, one of the dispensing tanks, the pump for supplying it, and means for controlling the pump, and

Fig. 3 is a detail view of the float-actuated, contact-carrying stem.

The hollow base 1 supports a dispensing reservoir 2, adapted to be supplied with the liquid from a suitable source, (not shown). The source may consist of a tank or reservoir embedded in the ground and adapted to communicate with an intake pipe 3, communicating with a pump 4, discharging

through a pipe 5 into the top of the reservoir 2. The impeller for the pump 4 may be connected to the drive shaft of a motor 6 supplied with current from a main service line consisting of the conductors 7 and 8, 55 which is tapped in a switch box 9 connected to the motor through the conductors 10 and 11. The switch box is provided with a reversing switch, as will be well understood, and it is adapted to be operated by a circuit energized by certain contacts in response to a float within the reservoir 2. For example, on the stem 12 projecting through the stuffing box 13 in the top of the reservoir 2 and within the contact casing 14 is a float 15, movable in response to variations of the oil level within the reservoir 2. The float stem carries one contact 16, which is adjustable and adapted to be received in the notched portions 17, 18 and 19 so that it 70 will operate at various levels of oil in the reservoir 2.

The switch controlling circuit consists of a conductor 20 in series with a battery 21. One end of the conductor is connected to 75 the switch box 9 and the other end to the live contact 16. At the upper end of the casing 14 is a contact 22 connected to a conductor 23, also connected to the switch box so that when the live contact 16 abuts 80 against contact 22, the switch will be operated to cut out the circuit for the motor 6. When the live contact 16 rests on the lower contact 24, connected to the conductor 25 leading into the box 9, the motor will be energized. 85

When the motor is energized, it will operate the pump 4 and pump oil into the reservoir until the level reaches the point at which the contact 16 is set, at which time 90 the contact 16 will contact with the contact 22, reversing the switch so as to break the circuit and causing the pump to stop.

The oil or liquid will remain in the reservoir until it is released by a manually operated releasing mechanism, which I will now proceed to describe.

The base 1 is divided into an upper compartment 26 and a lower compartment 27 by a lateral floor or partition 28. There is 100

a pull bar 29 for each reservoir having a hand hold or knob 30 on its end extending through the front wall of the base, and the opposite end is provided with a lateral projection or hooked end 31, which overlaps a complementary hooked end 32 on a valve-actuating rack bar 33. The valve-actuating rack bar has its upper edge 34 meshing at all times with the teeth 35 of the pinion 36 on the valve stem 37 to operate the valve in the discharge pipe 38 in the bottom of the reservoir 2 and communicating with the nozzle 39 adapted to be introduced into the filler tube of the motor vehicle receptacle to be filled.

Above the bars 29 and 33 is a coin chute 40, through which a coin, check or token may be introduced to drop in the space between the hooked end 31 and the hooked end 32, constituting a connector between said bars 29 and 33. When the coin drops between the bars, it will connect them so that when the pull bar is moved outwardly, it will impart movement to the rack bar 33 and thereby open the valve on the valve stem 37 and allow the oil to discharge from the reservoir 2 through pipe 38 and nozzle 39. When the rack bar 33 is moved forwardly, it will be held in that position by a pivoted pawl 41, carried by the floor 28 and having a rule joint connection 42 with a link 43 on the end of the eccentric bar 44 actuated by the eccentric 45 on the end of the drive shaft of the motor 6.

The rule joint will permit the pawl to give when the bar 33 is pulled outwardly to open the valve for the discharge of the liquid but will engage one of the ratchet teeth 46 to prevent a retrograde movement which the tension spring 47 may impart to it when it is unobstructed. The pawl will hold the bar out to keep the valve open until the contents of the reservoir 2 is discharged. When it has been discharged, the contact 16 will be resting on 24 so that the switch in the switch box 9 will close the circuit between the service line and the motor and cause the cam 45 to impart an oscillatory movement to the bar 44 and to move the toe of the pawl out of engagement with the ratchet and permit the spring 47 to retract the bar 33, thereby closing the valve in the pipe 38 so that the discharge will be closed at the time that the pump starts to operate to fill the reservoir 2.

It is to be understood, of course, that when the pull bar 29 is moved outwardly and is connected up to the bar 33, it will be effective in pulling the bar 33 until the coin registers with a slot 48, whereupon the bars 29 and 33 will be disconnected although the bar 33 will be held in its outward position by the pawl so that the valve in pipe 38 can remain open.

The mechanism described is for but one

of the reservoirs 2 and its complementary feeding and discharging mechanism, it being obvious that duplicate reservoirs 49 and 50 will be operated by identically the same mechanism except that all of the reservoirs in any bank can be connected up to the discharge pipe 38. The pump mechanism, coin-actuated mechanism, circuit control, etc., will be independent for each reservoir, however, so that one set of mechanism can operate independently of the other.

The advantage of having a plurality of reservoirs in one bank is that the consumer can exhaust first one reservoir and then the other without waiting for a re-filling of the reservoir which has just been exhausted and instead of connecting all of the reservoirs to a single discharge pipe 38, single discharge pipes can be provided if desired, so that more than one consumer can be supplied with gasoline at the same time.

What I claim and desire to secure by Letters Patent is:

1. A fluid dispensing device comprising a reservoir, means for introducing fluid into the reservoir, a discharge pipe leading from the bottom of the reservoir, a valve in the pipe having a stem provided with a pinion, a spring-retractable rack bar engageable with said pinion, means for operating the rack bar in opposition to the spring, a pawl to normally hold the rack in extended position, and means for moving the pawl out of engagement with the rack.

2. A fluid dispensing device comprising a reservoir, means for introducing fluid into the reservoir, a discharge pipe leading from the bottom of the reservoir, a valve in the pipe having a stem provided with a pinion, a spring-retractable rack bar engageable with said pinion, means for operating the rack bar in opposition to the spring, a pawl to normally hold the rack in extended position, and motor-actuated means for moving the pawl out of engagement with the rack.

3. A fluid dispensing device comprising a reservoir, a motor-actuated pump for supplying the reservoir with liquid, a pipe leading from the bottom of the reservoir, a valve in the pipe having a stem provided with a pinion, a spring-retractable rack meshing with the pinion, the spring being normally effective to hold the rack in a retracted position to maintain the valve closed, means for moving the valve against the action of the spring, a pawl for holding the rack in its non-retracted position, means for actuating the pawl connected to the motor, and means within the reservoir for causing the motor to operate when the means is in one position and to cause the motor to cease operating when the means is in the opposite position.

4. A fluid dispensing device comprising a reservoir, a pipe leading therefrom, a rack, a valve in the pipe having a pinion meshing with the rack, a spring for moving the rack in one position, an actuator for moving the rack in the opposite position, a pawl normally engaged by the rack, the pawl having a joint whereby the rack may tilt the pawl when it is slid in one direction and whereby the pawl will actively engage the rack to hold it against movement in an opposite direction, and means for actuating the pawl to release the rack.
5. In testimony whereof I affix my signature.

FRANK C. BATES.
